Attn:

UNITED STATES PATENT OFFICE.

FREDERICK G. GASCHLIN, OF SAN FRANCISCO, CALIFORNIA, ASSIGNOR OF NINE-SIXTEENTHS TO SIMON DAVIS AND MOSES DAVIS, OF SAN FRANCISCO, CALIFORNIA.

FIRE DETECTOR AND ALARM.

SPECIFICATION forming part of Letters Patent No. 698,003, dated February 11, 1902.

Application filed May 13, 1901. Serial No. 60,009. (No model.)

To all whom it may concern:

Be it known that I, FREDERICK G. GASCHLIN, a citizen of the United States, residing in the city and county of San Francisco, State of California, have invented an Improvement in Fire Detectors and Alarms; and I hereby declare the following to be a full, clear, and exact description of the same.

My invention relates to a device which I term a "fire detector and alarm."

It consists of a device adapted to be secured at points in rooms, buildings, vessels, and other structures which are liable to fires, electrical contacts insulated from each other, a spring, and destructible means for retaining said spring normally away from one of said contacts, which contact is made and the circuit completed by the destruction of the spring-retainer.

It also comprises details of construction, which will be more fully explained by reference to the accompanying drawings, in which—

Figure 1 is a general view of my device. Fig. 2 shows the device with its cover removed. Fig. 3 is a vertical section through the cover, showing the inside mechanism.

The object of my invention is to provide a means for detecting fires and for giving an alarm as soon as the fire is started.

As here shown, A is a base, of any suitable material. It is preferably made non-conducting and may be of wood, gutta-percha, or other suitable material, having the back grooved or channeled, as shown at 2, to receive and protect the conducting-wires 3, which lead through a suitable battery to an alarm of any desired description. The ends of these wires are secured by binding posts or nuts, as at 4, the posts or screws passing through the base A from the rear to the front. At the front they are connected, respectively, with plates 5 and 6. The plate 5 has secured to it an elastic spring, as 7. As here shown, this spring is made with a coil or turn, through which the post or screw 4 passes, and the upper edge of the plate is shown upturned and having a notch at 8, in which the upwardly-extending part of the wire lies, so as to steady it. The upper portion of the wire has a turn or coil which gives it sufficient

elasticity, and the other arm extends downwardly parallel with the first-named arm. Both these arms have hooks or turned-up portions, as at 9, and these are drawn together and connected by the destructible strip 10, so that when thus connected the second arm of the wire is kept out of contact with the plate 6, with which the second binding-post is connected. This plate 6 is so situated with relation to the first-named plate 5 that when the spring-arm is released it will fly out and contact with this plate 6, and thus complete an electrical circuit through an alarm of any suitable or desired description.

When the device is set for use, the spring-arm is drawn toward the fixed one, and the two are connected by the destructible plate 10, and thus retained in this position. This plate may be of fusible metal or any other suitable material. I prefer to make it of celluloid, which is easily ignited and destroyed by contact with flame and is also readily softened by considerable heat, such as would be produced by a fire.

The base and the attachments herein described are protected from injury by an inclosing cap or case 12, which fits over the base, and by means of screws or other fastenings the device is attached at any desired point. In order to enlarge the sphere of action of these devices, I have shown a destructible cord or fuse 13. This cord or fuse 13 is attached to a loop or hook 14, formed upon the plate 5, and extends down in close proximity to the destructible plate 10. This cord may have several branches extending out in different directions, so as to embrace a very considerable surface. The fuses are made of any material which will readily ignite. Such material is found in the market under the name of "celluloid wire," and it may be inclosed in a spiral coil of wire, as at 15, which serves to protect it from injury or breakage, at the same time admitting free access of fire or heat to the fuse. The fuse may be otherwise protected, and it may, if desired, lead through guiding loops or staples where changes of direction are made or where it is desirable to keep it out of actual contact with walls or surfaces.

The inclosing casing or guard for the ap-

paratus may be perforated with slits or openings, through which the interior can be seen, but which will serve to keep out mice or vermin and protect the destructible strip or plate from injury.

The operation would then be as follows: Fire occurring anywhere within reach of either of the fuses or near the device itself will be carried directly into the apparatus by 10 the burning of the fuse, and as this is in close contact with the strip or plate 10 the latter will be destroyed or so softened that the tension of the spring will break it. The spring then expands and makes an electrical contact 15 and circuit between the posts 4, and thus through the wires 3 to the alarm.

The spiral wire or equivalent inclosure for the fuse serves, in addition to the protection afforded, to regulate the rate of burning and 20 prevent too rapid combustion or the breaking of the fuse while burning. If by accident the fuse should be broken or separated, the spiral or inclosure will still hold the parts near together, so that fire could be communicated 25 between them. In passing through walls, beneath work-benches, and under similar conditions the inclosure for the fuse may be a properly-supported tube, as at 16, having an open slot on the outside to admit fire or regulate 30 the burning, while affording complete protection. Holes made through the tube at any desired point allow branches of the fuse to connect with the main portion, as before described.

35 Having thus described my invention, what I claim as new, and desire to secure by Letters Patent, is—

1. A fire detector and alarm including a normally broken electrical circuit, a spring bent 40 or returned substantially upon itself to form two arms one of which is normally connected to a contact, and the other is movable said movable arm adapted to be drawn toward the fixed arm, and a destructible strip connected 45 to both arms and holding the movable arm normally away from its contact.

2. A fire detector and alarm, consisting of an insulating - base with binding - posts and contacts, a spring bent at its central portion 50 to form two arms one of which is fixed to one of said contacts and the other is movable, and a destructible strip extending from the extremity of one arm to the other, and holding the movable arm normally away from its contact.

3. A fire detector and alarm consisting of an insulating-base, separated contact-plates fixed thereto, binding-posts for connecting of electrical conducting-wires, a spring consisting of a strip coiled at its center and returned 60 substantially upon itself to form two arms, one of which is secured to one of the contact-plates, upturned ends to the arms, a destructible strip engaging the upturned ends of the arms and connecting said ends when the 65 other arm has been drawn away from its contact-plate.

4. A fire detector and alarm, consisting of an insulating-base, separated contact-plates and electrical connections carried thereby, a 70 two-armed elastic spring, one portion of which is fixed to one of the contact-plates, and both arms having upturned ends, a destructible strip connecting said upturned ends and disconnecting a movable arm normally away 75 from its contact-plate, an ignitable fuse or cord, and means for attaching it contiguous to the destructible strip, said fuse extending outside of the device.

5. A fire detector and alarm, consisting of 80 an insulating-base, contact-plates and electrical connections secured thereto, a two-armed spring, means by which one of said arms is secured to one of the contacts, a de- 85 structible strip, and means for connecting it with the spring-arms whereby the second arm is normally held away from its contact-plate, a hook formed upon the first-named contact-plate, contiguous to the destructible strip, an ignitable fuse or cord attached to said hook, 90 extending away from the device, and having branches divergent from each other.

6. A fire detector and alarm, consisting of an insulated base, contact-plates and electrical connections carried thereon, a spring 95 attached to one of said plates having an elastic arm adapted to form contact with the other of said plates, a destructible strip by which said arm is normally retained out of contact with its plate, means for incoming fire or heat 100 to destroy said strip, and an inclosing perforated casing by which the device is covered and protected from injury.

In witness whereof I have hereunto set my hand.

FREDERICK G. GASCHLIN.
